(57) **CLAIM**

The ornamental design for a cloud-shaped display placard, as shown and described.

DESCRIPTION

FIG. 1 is a front-view illustration of a cloud-shaped display placard according to the present invention;
FIG. 2 is a rear-view illustration of the cloud-shaped display placard;

FIG. 3 is a right, side-view illustration of the cloud-shaped display placard;

FIG. 4 is a left, side-view illustration of the cloud-shaped display placard;

FIG. 5 is an enlarged top-view illustration of the cloud-shaped display placard; and,

FIG. 6 is an enlarged bottom-view illustration of the cloud-shaped display placard.

The broken lines shown in the drawings represent unclaimed portions of the design and form no part thereof.
